[57] CLAIM

The ornamental design for a belt attachable watertight container, as shown.

DESCRIPTION

FIG. 1 is a top perspective view of a belt attachable watertight container, showing my new design;

FIG. 2 is a bottom perspective view thereof;

FIG. 3 is a top perspective view thereof with the cover removed;

FIG. 4 is a bottom perspective view of the cover;

FIG. 5 is a cross-sectional view thereof with the cover in place;

FIG. 6 is a bottom plan view thereof;

FIG. 7 is a front elevational view thereof;

FIG. 8 is a top plan view thereof;

FIG. 9 is a side elevational view thereof; and

FIG. 10 is a rear elevational view thereof.
